UNITED STATES PATENT OFFICE.

EDWARD DORR, OF PRINCETON, KENTUCKY, ASSIGNOR OF ONE-FOURTH
TO VALENTINE DORR, OF SAME PLACE.

AUTOMATIC RAILWAY-GATE.

SPECIFICATION forming part of Letters Patent No. 600,307, dated March 8, 1898.

Application filed August 17, 1897. Serial No. 648,566. (No model.)

To all whom it may concern:

Be it known that I, EDWARD DORR, residing at Princeton, in the county of Caldwell and State of Kentucky, have invented a new and useful Automatic Railway-Gate, of which the following is a specification.

This invention relates generally to gates for the protection of railroad tracks, yards, &c., and more particularly to an improved cattle-gate constructed so as to be automatically operated by the passage of a train over the track to which it is attached.

The object of my invention is to provide a new form of laterally-movable gate for the exclusion of cattle, stock, &c., from the tracks or yards of a railroad which shall be cheap in construction, automatic in operation, and easily applied.

Another object is to provide a cattle-gate which shall be quick and certain in its movements and regulated in its operations by a train passing over the track to which it is attached.

Another object of my invention is to provide a cattle-gate which may be applied to any railroad-track at any point where a section of said track is desired to be closed—such as stock-yards, roundhouse-yards, station-yards, and fenced sections of said track along the line of said road.

With these objects in view my invention consists in the peculiar construction of the various parts and in their novel combination and arrangement, all of which will be described in detail, and pointed out in the claims.

In the drawings forming a part of this specification, Figure 1 is a perspective view showing my invention in use. Fig. 2 is a top plan view showing the gates in a separated or open condition and the track unobstructed. Fig. 3 is a similar view with the gates closed. Fig. 4 is a cross-section through the track and the gate-base, the gates being closed.

Like letters and figures of reference mark the same parts wherever they occur in the various figures of the drawings.

The description and operation of my invention are as follows:

A A represent the rails of the regular track. B B are narrow curved rails slightly elevated in their middle above the regular track,

but sloping toward the ends, which are below the level of the regular track. These rails are placed parallel and adjacent to the regular rails and supported at each end by an iron bar *a*, extending below the road-bed and bent in a right angle at its union with the rails B B, so as to form a shoulder, from which an arm *b* extends and connects with upper arm 1 of a bell-crank lever. This lever is pivoted 60 to a post P, resting upon a cross-tie.

C C are cross-ties, upon one of which a bed-plate E is attached. Upon the cross-tie the brace-levers F F and F' F' are pivotally fastened near their bottom, while they support 65 and are pivotally attached at their top to the gates G G. The connecting-rods g g extend inward below the road-bed from the lower end of the brace-levers F' F' to the ends of the shear-levers H H, which rest below the 70 center of the road-bed, the opening and closing of said shear-levers closing and opening the gates G G alternately. At the opposite ends of the shear-levers H H are attached rods h h, which connect with the lower arm e of the 75 bell-crank lever and operate in connection with the downward pressure of the side rails B B, so that when the passing train presses down upon said rails B B the combination movement of the bell-crank levers e e and the 80 connecting-rods h h closes the shear-levers H H, and thus by means of the rods g g opens the gates.

Attached to the bottom of the gates G G are cables or chains I I of steel wire or other 85 suitable material, which extend downward through openings in the bed-plate and cross-tie into tubes K K, set in the ground. In these openings in the bed-plate are pulleys J J for the assistance of the cables I I. 90 Weights W W are attached to the ends of said cables, and when the pressure upon the rails B B is released by the passing of the train the weights W W pull downward in the tubes K K with sufficient force to close the 95 gates automatically. Upon opposite sides of the center tie and bed-plate on which the gates G G are mounted are two diagonally-extending cables L L, (shown in dotted lines in Fig. 4,) which cables connect the lower end 100 of the pivoted brace-lever F' of one gate with a point upon the lever F' on the opposite side

of the track above the pivot of said lever, so that in case the train in passing over the track should miss either one of the rails B B the pressure upon the one passed over would be communicated by said cables L L to the opposite lever, so as to open both gates just the same as if both rails had been traversed by the train.

The operation of my device is as follows:
 10 The train as it approaches the gates touches the narrow projecting rails B B, pressing them downward. This causes the iron bar a, which is riveted to the rails B B, to move downwardly, carrying with it the links l l and
 15 the upper arms of the bell-cranks, causing the lower arms of said levers to move outwardly, which movement operates to close the shear-levers and open the gates G G by means of the connecting-rods g g. As soon
 20 as the downward pressure upon the rails B B is released by the passage of the train the weights W W move downwardly in the tubes with sufficient force to operate the levers F' F' and the rods g g and close the gates automatically.
 25

It will be seen that my invention is simple in construction, easy of operation, and convenient in application.

Having thus fully described my invention, 30 what I claim as new, and desire to secure by Letters Patent, is—

1. In a cattle-gate for railroad-tracks, the combination with the bed-plate and cross-tie, of two gates adapted to move in opposite directions, supporting-braces pivotally connecting them with the bed-plate, a pair of shear-levers, rods connecting the braces and shear-levers, auxiliary movable rails, a cross-bar connected to said rails, a bell-crank lever, a
 35 link connecting one end thereof with said bar, and rods connecting the other end of the bell-crank with said shear-levers, whereby the movement of the rails operates the rods and levers to open and close the gates, sub-
 40 stantially as set forth.
 45 2. In a cattle-gate for railway-tracks, the

combination of two gates adapted to move laterally across the track, pivotal levers upon which said gates are supported, shear-levers pivoted to the cross-ties, rods connecting them at one end to the pivotal levers, at a point below the pivots, vertical bell-crank levers on each side of the track, rods connecting the lower arms of the bell-crank levers with the opposite ends of the shear-levers, 55 auxiliary tracks, and connection between said auxiliary tracks and the upper arms of the bell-crank levers, whereby the downward pressure upon the auxiliary tracks will operate the gates, substantially as described. 60

3. In a cattle-gate for railroad-tracks, the combination with two pivotally-mounted gates adapted to move laterally across the track, of weights attached to the bottom of the gates and adapted to move freely in tubes placed beneath the track, said weights being so adjusted as to move downward in said tubes upon the release of the pressure upon the auxiliary track, whereby the gates are automatically closed, substantially as shown 70 and described.

4. In a cattle-gate for railway-tracks, the combination with two gates adapted to move laterally across the tracks, of a cross-tie, 75 gate-supporting levers pivoted thereto outside of the track, auxiliary tracks, connecting mechanism whereby the gate-supporting levers are operated when said tracks are depressed, and connections between the lower end of the gate-supporting lever on one side 80 of the track and the gate-supporting lever on the other side of the track, at a point above its pivot, whereby the motion of one supporting-lever is transmitted to the other in opposite directions, and both gates caused to be 85 opened by pressure upon either auxiliary track, substantially as described.

EDWARD DORR.
